(57) **CLAIM**

The ornamental design for a smokeless tobacco container holder, substantially as shown and described.

DESCRIPTION

FIG. 1 is a front and left side perspective view of a smokeless tobacco container holder showing my new design, with the holder in a closed configuration;

FIG. 2 is a front elevation thereof.

FIG. 3 is a rear elevation thereof.

FIG. 4 is a top view thereof.

FIG. 5 is a bottom view thereof.

FIG. 6 is a right side elevation thereof, the left side being a mirror image of the right side.

FIG. 7 is a left side rear perspective view thereof.

FIG. 8 is a front and left side perspective view, showing the holder in a partially open configuration;

FIG. 9 is a front and left side perspective view, showing the holder in a partially open configuration;

FIG. 10 is a front elevation of the holder in the open configuration of FIG. 9.

FIG. 11 is a rear elevation of the holder in the open configuration of FIG. 9.

FIG. 12 is a right side elevation of the holder in the open configuration of FIG. 9, the left side being a mirror image of the right side.

FIG. 13 is a top view of the holder in the open configuration of FIG. 9; and,

FIG. 14 is a bottom view of the holder in the open configuration of FIG. 9.

Environment is indicated by “dash-double-dot” lines, whereas in FIGS. 3, 7, and 11, the dashed lines indicate stitching which forms part of the claimed design.

In all Figures, shading accords to the lighting convention described in 37 C.F.R. § 1.84(m).

The broken line showing of environment in the drawings is included for the purpose of illustrating only and forms no part of the claimed design.
